UNITED STATES PATENT OFFICE.

JAMES H. HARDY, OF WACO, TEXAS.

TROUSERS-GUARD.

SPECIFICATION forming part of Letters Patent No. 703,579, dated July 1, 1902.

Application filed August 29, 1901. Serial No. 73,757. (No model.)

To all whom it may concern:

Be it known that I, JAMES H. HARDY, a citizen of the United States, residing at Waco, county of McLennan, and State of Texas, have 5 invented a certain new and useful Improvement in Trousers-Guards, of which the following is a specification.

My invention relates to a new and useful improvement in trousers-guards for bicycleriders, and has for its object to provide a trousers-guard which will hold the leg of the trousers rigid and not allow the same to come in contact with the chain or other working parts of the bicycle, but will at the same time 15 preserve the shape of the trousers, and the guard will be entirely out of sight.

With these ends in view this invention consists in the details of construction and combination of elements hereinafter set forth and 20 then specifically designated by the claims.

In order that those skilled in the art to which this invention appertains may understand how to make and use the same, the construction and operation will now be described in detail, referring to the accompanying drawings, forming a part of this specification, in which—

Figure 1 is a perspective view showing my invention applied, and Fig. 2 a perspective 30 view of the guard by itself.

The guard is formed, as shown in Fig. 2, with an outside rim, which is heart shape in outline, and a circular portion A is formed within the heart-shape portion and connected to the same by the parallel portions B. This leaves a throat C connecting the circular portion A with the outside. The material of which the guard is made is spring metal, and when the guard is applied the circular portion is adapted to embrace the foot just above the ankle and is applied by forcing the guard upon the ankle by spreading the throat C, which will spring open far enough to allow the foot to enter through the same into the circular portion A, when it will again spring back in its normal position. The leg of the trousers is then pulled down over the guard, and the outside rim D will keep the trousers at a slight distance from 45 the foot, but will keep the trousers from coming in contact with the working parts of the bicycle because of the fact that the guard

is much longer from the front to the rear than across the same, and to keep the trousers from working up above the guard they are pinned to the guard by means of the safety-pins E, which are secured to the guard at different points and adapted to pass through the trousers. For the purpose of adjusting the guard to different-size trousers I make 60 the front of the guard F adjustable. The ends of the body portion are slotted at G, and upon one side a pin H is secured in one end of the adjustable portion F and passes through this slot and has an enlarged head 65 formed upon the same outside of the end of the body portion. A slot is also formed in this end of the adjustable portion F, and a pin I is secured within the end of the body and passes through this slot and is headed upon 70 the inside. Thus the adjustable portion F can be pressed inward or pulled outward to a distance limited by the length of the slot. Upon the opposite side instead of the pin a thumb-screw J passes through the slot G, and when 75 the adjustable portion F is once adjusted this thumb-screw is tightened so as to hold the two parts of the guard rigidly together.

The advantage of my invention is that the guard will effectually keep the trousers-leg 80 in such a position that it will not come in contact with the working parts of the bicycle, and it does not detract from the appearance of the trousers-leg, as the guard is entirely out of sight, and thus it may be worn 85 either on or off the wheel and is quickly and easily removed or applied when desired.

Of course I do not wish to be limited to the exact construction here shown, as slight modifications could be made without departing 90 from the spirit of my invention.

Having thus fully described my invention, what I claim as new and useful is—

1. In a device of the character described, a strip of spring metal bent to form the body portion, as shown and described, a V-shaped front portion, each prong of the V-shaped portion adapted to be adjusted longitudinally of the guard upon the ends of the body portion, and pins secured to the outside of the guard for the purpose of securing the trousers-leg to the same, substantially as and for the purpose specified.

2. In a device of the character described,

an interior circular portion adapted to embrace the foot above the ankle, a throat extending outward from the interior of the circular portion to the exterior of the guard,
5 parallel portions forming the sides of said throat and adapted to connect the circular portion with the exterior rim, the front portion of the exterior rim adapted to be formed independent of the rear portion, means for
10 adjusting the front portion longitudinally relative to the rear portion, both the front and rear portions adapted to be formed of

spring metal, and means secured to the exterior rim for securing the trousers-leg to the guard, substantially as and for the purpose 15 set forth.

In testimony whereof I have hereunto affixed my signature in the presence of two subscribing witnesses.

JAMES H. HARDY.
